UNITED STATES PATENT OFFICE.

VAL DE MAR SLEIGHT, OF NEW YORK, N. Y., ASSIGNOR OF ONE-THIRD HIS
RIGHT TO JESSE H. GIFFORD, OF SAME PLACE.

IMPROVEMENT IN COMBINED RECLINING AND INVALID CHAIRS.

Specification forming part of Letters Patent No. **172,665**, dated January 25, 1876; application filed
October 22, 1875.

To all whom it may concern:

Be it known that VAL DE MAR SLEIGHT, of the city of New York, N. Y., invented a new and useful Improvement in Combined Reclining and Invalid Chairs, of which the following is a specification:

The invention relates to reclining and invalid chairs; and has for its object the production of a chair which possesses the advantages of an ordinary rocking-chair, and is at the same time so constructed that it may be adjusted and arranged to form what is generally known as a reclining-chair, besides admitting of adjustment so as to be available as a cot or cradle. While effecting in a convenient manner the offices of any of these articles at will, its construction is such that its parts may be made of light material, and the whole folded together so as to occupy but little space, and be readily portable. The elements of novelty and the details of construction and operation are fully set forth herein-after.

In the accompanying drawings, Figure 1 is a side elevation of a device embodying the elements of the invention. Fig. 2 is a central longitudinal section of same. Fig. 3 is a side elevation, showing the device in the form of a cot.

A are rockers, of usual construction, adapted in size and shape to the other parts of the device. Near their forward ends are hinged the inclined pieces B, which are beveled and tongued at their lower extremities, the tongues fitting in slots or cavities in the rockers, so as to give the pieces the proper inclination, and to insure security. The pieces B extend upward, and are connected with the transverse bar C, so as to turn upon it, their inner surfaces being in immediate proximity to the back pieces D. To the upper ends of the pieces B are hinged the arms E, their forward extremities being provided with a groove or notch, and arranged to fit upon the projecting ends of the transverse bar H, being held in place by the buttons or washers h.

I are cross-pieces, which are pivoted at about their middle parts to the pieces B, and which are beveled and flanged at their lower extremities, the flanges being upon the inner sides and

fitting in cavities or seats in the rockers, (or arranged in some other convenient way,) and connected therewith by means of thumb-screws, so that they may be readily disconnected or secured in place. The upper ends of the pieces I are provided with apertures, through which the bar H passes, the piece I turning when the parts are unlocked. Upon the upper side of the piece I are the ratchets or notched pieces K, which are arranged with relation to the pawls d upon the lower ends of the back-pieces D.

The back-pieces D are connected by interior cross-pieces, and turn upon the transverse bar C, which passes through apertures cut to receive it. Near the lower ends of the pieces D are pivoted the stays or levers L, having the slots l, which move upon the pins or thumb-screws o, upon the inner sides of the pieces I, the pins or thumb-screws being in the slot, and so arranged that they may be turned to permit the stay or lever to be carried out of position and folded at pleasure with the other parts.

The levers L are straight, as in the present instance, or may be curved, the forward ends being carried upward, and the rear ends inclined in a contrary direction. The office of the levers L is to support the foot or leg piece of the device, and their length is such as to effect this result, while the slots l serve, in combination with the pins o, to hold the back at a suitable inclination when the device is in use as a rocking-chair. The bars C and H are seat-pieces or rounds, of usual construction. To the former is attached, in any appropriate manner, the piece of textile fabric or other like material M, which is supplied with a strap, m, and buckle n, by means of which it is held in place, so as to form a seat or section of a cot at will. One end of the piece M is free, and is passed between the bar H and foot or leg piece, and secured by the strap and buckle as desired. The foot or leg piece consists of two frames, N O, of unequal size, hinged together, the upper, which is the larger, being intended to support the legs, and the lower to serve especially as a foot-rest. The frame N is attached to turn upon the bar or round H, and has secured at one side the eye p, in which the hook P is inserted when it is desired to

adjust the lower frame O to be used as a foot-rest. Another eye, p' , is attached to one of the rounds, or in any convenient position, in which the hook P is placed when it is desired to adjust the parts for use as a rocking-chair. Attached to fold between the back-pieces and within the frame N are the legs R R', which are of such length, respectively, that, when lowered, the back and leg and foot rest and seat will be in substantially the same horizontal plane. The legs are secured in place in any convenient manner, and are of the requisite strength to effect their offices.

The frames and back are covered with canvas, or cushioned, or otherwise constructed; but the flexible seat-piece M or its equivalent is an essential feature, and will be used in all cases.

The operation of the invention is as follows: To use it as a rocking-chair, adjust the parts and secure them in place as follows: Fasten the inclined pieces B I to the rockers, place the pawl in connection with the lowest notch in the ratchet, buckle the seat strap or piece M, and place the hook P in the eye p' . The result will be that all the parts are made rigid as against any backward movement of the body, the whole forming an ordinary rocking-chair.

To use the device as a reclining-chair, remove the hook P, place it in the eye p , and elevate the pawl d to the desired notch. By this means the parts are freed and a reclining-chair results. The levers L, when the back is carried down, are forced forward, thus sustaining the frame N. The pawls d may be thrown back or placed upon the ratchets, so as to permit of an adjustment of the back at any angle.

To use the device as a cot, drop and adjust the legs R R'; and to use it as a cradle, raise the legs and fold the back upon the seat-piece M, having previously freed the levers L from the set-screws o.

To fold the device, free the piece M, levers or stays L, lower ends of the pieces I, and forward ends of the arms D, when the parts may be folded upon each other to form a relatively small and compact body.

The details of construction and operation, other than as hereinbefore set forth, will appear from the drawings, or require no explanation.

What I claim as my invention, and desire to secure by Letters Patent, is—

1. The rockers A, inclined pieces B, hinged thereto and to the arms E, and bar C, in combination with the bar H and inclined piece I, attached to the rockers A, all substantially as shown and set forth.

2. The back-pieces D, provided with the pawls d , in combination with the ratchets K, levers L, frame N, and legs I and B, substantially as shown and described.

3. The piece M, provided with buckle n and strap m , substantially as shown and described, and for the purposes set forth.

4. The combination of the frames N O, and hook P, and eyes p p' , for the purposes specified.

5. The rockers A, pieces B and I, bars C and H, back-pieces D, levers L, and frame N, in combination, substantially as described, and for the purposes set forth.

6. The rockers A, pieces B and I, bars C and H, back-pieces D, levers L, frame N, piece M, and arms E, in combination, all operating substantially as shown and described, and for the purposes set forth.

In testimony that I claim the foregoing improvement in folding chairs, as above described, I have hereunto set my hand and seal this 2d day of October, 1875.
